SPORTS GAME SCORE RECORDER OR SIMILAR ARTICLE

Robert Felt, 57-42 244th St., Douglaston, N.Y., and
Louis Ratner, 87 Academy St., Liberty, N.Y.

Continuation of design applications Ser. Nos. 83,174 and 83,181, Dec. 28, 1964. This application Sept. 17, 1965,
Ser. No. 87,245

Term of patent 3½ years

(Cl. D34—5)

FIG. 1 is a front elevational view of a sports game score recorder or similar article.

FIG. 2 is a side elevational view.

FIG. 3 is a rear elevational view.

FIG. 4 is a top plan view.

FIG. 5 is a bottom plan view.

FIG. 6 is a cross section view taken on line 6-6 of FIG. 3.

FIG. 7 is a front elevational view of a sports game score recorder or similar article wherein the top fourth of the central window is narrower and the remaining lower portion thereof is wider than that seen in FIG. 1.

FIG. 8 is a side elevational view.

FIG. 9 is a rear elevational view.

FIG. 10 is a top plan view.

FIG. 11 is a bottom plan view.

FIG. 12 is a cross section view taken on line 6-6 of FIG. 9.

The present application is a continuation over applications Serial Nos. D. 83,174 and D. 83,181, both filed December 28, 1964.

We claim:

The ornamental design for a sports game score recorder or similar article, as shown and described.
